ROOF DEMONSTRATOR

Annon W. Holt, Long Beach, Calif.

Application April 30, 1931, Serial No. 534,117

6 Claims. (Cl. 35—16)

My invention relates to means for demonstrating quantity requirements of roofing materials as applied to various types of roof designs, particularly roof designs of the hip-and-valley construction. Those concerned in the art of roofing find difficulty in figuring the quantity in square foot area of roofing material necessary to be applied on roofs having gables and dormers, and are liable to mis-calculate the amounts required. It is the purpose of the present invention to provide a novel demonstrating device whereby it can be visually understood and demonstrated that so long as the pitch of a roof is the same over its entire surface all roofs are plain gable roofs so far as the amount of roof-surface is concerned and that the ratio of roof-surface to its flat or horizontal plan surface is the same and that the same amount of material is required to cover one design of roof as the other regardless of the number of gables, providing that the pitch of each gable is of the same angle. The device also demonstrates that adding a dormer increases the roof surface only to the extent that the dormer roof projects over and duplicates the main roof, and that the walls of a dormered gable are equal to those of a plain gable.

The objects of the invention are, first, to provide means within the construction of the device for demonstrating the area of various types of roof designs; second, means for quick interchange of parts from one design to another; third, to provide facilities for readily assembling or disassembling the various parts; and fourth, to provide space within the main body portion of the device for containing the various members when disassembled and for compactness of form for shipment. I accomplish the above objects by the arrangements and combinations of the parts disclosed in the accompanying drawings, in which— Figure 1 is a view in sectional elevation taken on line 1—1 in Fig. 2 showing various members set up ready to receive the roofing sections of a four-gabled roof design; Figure 2 is a plan view of the device with members arranged as in Fig. 1 with the roofing sections added and indicated by the dotted lines; Figure 3 and Figure 4 are fragmental views showing modifications to be fully described later; Figure 5 is a sectional detail view taken on line 5—5 in Fig. 3; Figure 6 is a similar view taken on line 6—6 in Fig. 2; Figure 7 shows a complete layout in plan view of a full set of roofing sections, and how the material would be bisected to avoid waste in covering any of the roof designs shown in Figures 10 to 14 inclusive; Figure 8 shows two sections of the roofing material as they

would appear before being bisected along the dotted lines to produce sections for the roof of the dormer shown in Fig. 10; Figure 9 shows dormer roofing sections after being bisected; Figure 10 shows a roof design having two gables and one dormer; Figure 11 shows a roof design having four gables, and an arrangement to be applied for demonstration with the set-up shown in Figs. 1 and 2; Figure 12 shows a roof design having three gables; Figure 13 shows a design of roof having two gables at right angles and two straight sided hips; Figure 14 shows a plain four sided hip roof, and without gables or dormers; Figure 15 shows in plan view an arrangement of a gable front, divided into three sections for the purpose of forming the gable front wall and two side walls of a dormer, and with the end pieces extending straight outward as they would be when used as an ordinary gable front, and with the end pieces shown dotted at right angles in which position they would form the side walls of a dormer; Figure 16 shows a face view of the dormer gable, with the end pieces arranged in similar position as that in Fig. 15; Figure 17 is an enlarged view of one of the mitered joints of the gable front shown in Figures 15 and 16, taken on line 17—17 in Fig. 16, with the end piece shown at right angles.

In Fig. 1 the side walls 18 represent the outer walls of a building, members 19 represent the end walls of the gables, and 20 are hinges securing the gable members to the walls 18 and are provided to permit the members 19 to be turned inward and out of the way when demonstration of a plain hip roof as in Fig. 14 is to be made. 21 is a center-post shown secured in the socket 18a and held in place by the screw 18b; 18c is a shelf provided with an opening closely fitting about the center-post and directly centered over the socket 18a for the purpose of maintaining the post 21 in vertical position, while at the upper end of this post there are secured the ridge bars 22 by means of the hinges 23 for the purpose of permitting the ridge-bars to be lowered into the dotted position as shown at 22'. When it is desired to disassemble the parts the screw 18b is removed and post 21 withdrawn from its socket, and together with the members 22 they are placed in the container compartment 18d.

Imbedded in the outer ends of the ridge-bars 22 are the tongue-pins 22a provided for the purpose of retaining the ridge-bars 22 in their horizontal position and to prevent the gable-fronts 19 from collapsing inward due to the abutting effect of the outer ends of members 22 contacting with

the inside faces of 19, and at the peak of each gable front are notches 19' adapted to receive tongue-pins 22a and prevent lateral movement of the members 22. At 24 are shown pins projecting from the sides of the ridge-bars provided to receive and retain the roofing sections marked X in position during demonstration of the gable designs shown in Figures 10 to 13 inclusive; and at the inner ends of the ridge-bars 22 pins 25 are provided to receive two roof sections X during the demonstration of a straight sided hip or a plain hip roof design as indicated in Fig. 14; these pins are elevated into the position as shown in Fig. 6 ready to receive the sections X when the members 22 are lowered as indicated at 22' Fig. 1, and in the fragmental view Fig. 6.

In Fig. 2 all of the gable front members 19 are shown in vertical position, and the ridge-bar members 22 in their horizontal positions ready to receive the roofing sections X, as indicated by the dotted lines; the edges a, a then abutting and forming the ridge of a roof design, the edges b, b abutting and forming the valleys, and the edges c represent the eaves of the roof. In Figs. 3 and 10 to 16 the side-walls are broken away for convenience of illustration.

In Fig. 7 are shown eight sections X of the roofing material which are sufficient to demonstrate all of the roof designs shown in Figures 11 to 14 inclusive. By referring to the drawings, it will be readily seen how the sections X are applied in the different roof designs. For example in Fig. 11 a four gabled roof is demonstrated by raising the four gable-fronts to vertical position and locking them by the ridge-bars 22 as shown in Fig. 1, and then applying the eight roof sections X in pairs to the pins 24 as shown in Fig. 2, with their edges a abutting and forming the ridges of the gables, their edges b abutting and forming the valleys between adjacent gables, and their edges c forming the eaves of the roof. When it is desired to demonstrate a three gabled roof as in Fig. 12, one of the ridge-bars 22 is lowered into position as 22' in Fig. 1 and its gable front folded inward, and the roofing sections X are again applied with two of the sections supported by the pins 24 and slotted openings x, and with the two middle sections inverted and supported by the pins 25 and openings x', thus forming a plain hip-side as indicated at 12a in Fig. 12. To form a plain gable roof, the vertical gable-front in Fig. 12 is lowered, and the roof sections on that side are inverted to form a plain hip side as indicated at 12a in that figure. To form the roof design shown in Fig. 13, two of the ridge-bars 22 are lowered together with their gable fronts and the roofing sections are again applied and two plain hip-sides are set up as shown at X, X in Fig. 13. When all four ridge-bars and all four gable fronts are lowered, the plain hip type of roof design may be demonstrated as shown in Fig. 14 by applying all of the sections X in the inverted position and with the pins 25 in the openings x'.

To demonstrate a dormer set-up as shown in Fig. 10 four sections X are applied on the plain hip-side and two on the dormer side as there shown, with two sections Y for the dormer roof and two extra sections Za each of sufficient size to form the main roof at one side of the dormer and to duplicate the extent of the projection of a section Y over the main roof. This demonstrates that adding a dormer increases the total roof surface only to the extent that the dormer roof projects over or duplicates the adjacent main

roof. Preferably, in demonstrating a dormer and to show that the walls of a dormered gable are equal to those of a plain gable, I convert the gable front into the construction as shown in plan view in Fig. 15, made up of three sections 19, 19a and 19a (Fig. 17) with beveled joints having abutting faces 26 and 27; and in the face 27 I provide a groove 29 adapted to receive a tongue-rib 28 formed upon the face 26; and to maintain the faces in contact with each other I provide a spring indicated at 30, having its ends extending through openings 31 of member 19 and openings 32 and 33 of the sections 19a and clinched at 34; this provides tension between the sections 19a, 19a, for maintaining them in position against the abutting faces when straight outward as shown in Fig. 16 for use as a plain gable-front or at right angles as in Fig. 17 for use as a dormer gable-front; and by having the ends of the spring 30 thread through the openings 31 and 32, and locating said openings midway of the bevel joints, I provide a suitable means to allow the sections 19a to be turned over and into inverted position as indicated at 19a, 19a in Fig. 10 and thus form the dormer's sides, and 19 forming the dormer gable front. Then by applying the roofing sections marked Y and Za of Fig. 10, a dormer demonstration is shown; and to prevent the sections Za slipping down or dropping inward I provide wire clips Z, Z', as indicated in Fig. 10, their upper ends being turned downward to enter indentures provided in the face of sections X. The sections Y are provided with openings x to engage pins 24 on the associated ridge bar.

In Fig. 3 a modified form of construction of the ridge-bars is shown made of two sections with a buggy-stay joint as at 35 which when in the raised position, as shown by the full lines, will prevent the gable front 19 from folding inward; this type of ridge-bar may be constructed of sheet metal formed into trough-shape having the pins 24 formed thereon together with the hinges 36 and 37, the hinge 36 being secured to the center-post 21 while hinge 37 is attached to the gable front 19. This arrangement when folded inward as indicated by the dotted lines provides for the joint 35 to rest upon the side of post 21 with the link 38 hanging downward and link 39 acting as a prop for the gable front 19 and holding it at an angle equal to the pitch of the roof, whereupon the roofing sections X may be placed for demonstration of a plain hip side and held by any suitable means as pins 19b.

In Fig. 4 a modified form of ridge-bar is shown that has the advantage of collapsing into compactness for shipment like the construction indicated in Figures 1 and 2, and also permits the gable fronts being held at the pitch line as in Fig. 3 when demonstrating the hip type of a roof. This view shows the ridge-bar constructed of sheet metal and of the same trough-like shape as indicated in Fig. 3 and in cross-section in Fig. 5, and having formed thereon the pins 24. This type of ridge-bar may be made in one piece throughout its full length, with a hinge 40 for attaching to the gable fronts, and with a flat blunt projecting end 41 provided to catch in or be inserted into the grooves 42 which are formed in post 21 near the top and indicated in this figure. In this modification I have omitted the shelf 18c and instead of using a shelf I provide the post socket 18a with sufficient depth to maintain the center post in its vertical position and at the same time form a suitable structure upon which the ends 41 may rest while the ridge-bars are

holding the gable fronts at an inclined position as in Fig. 3 for receiving the roofing sections on pins 19c.

The various parts of the construction may be 5 made of wood or fibrous material or metal without departing from my invention.

By comparison of Figs. 2 and 7 it is obvious that the roof-surface of the former is the same as the flat or plane surface of the latter, assuming that the sections in the two figures are of 10 equal size, and by comparison of these figures with the forms shown in Figs. 11 to 14 it is obvious that all these roofs are of the same area, assuming that the roof-pitch is the same. The 15 device, when used as above described to exemplify these various roofs, visually demonstrates that all are in effect plain gable roofs so far as the amount of roof surface is concerned and require the same amount of material regardless of the 20 number of gables, or hips, or valleys, or the direction in which any portion or portions of it may slope. Also, it being well-known that the area of a roof-surface is a certain percentage greater than that of the horizontal plane or flat surface 25 under it and varying according to the pitch of the roof, the device when used as above described demonstrates that all roof surfaces having the same pitch bear the same ratio or percentage of increase to the corresponding horizontal plane 30 (Fig. 7) regardless of the flat contour of their surfaces due to the absence of gables as in Fig. 14, or of the irregular contour of their surfaces due to their rise and fall over its gables as in Figs. 35 11 to 13. Therefore, the cost of the flat surface (Fig. 7) in terms of roof-costs being known, the cost of the roof in square foot area of roofing material is easily figured by merely adding a certain percentage corresponding to the pitch or steepness of the roof, and the necessity of calculating 40 the areas of roofs having hips and valleys is eliminated. The device thus provides means to quickly and easily demonstrate that so long as the pitch is the same all these roofs bear the same ratio to the horizontal plane under the 45 roof and that the same amount of material is required for one design of roof as the other regardless of the direction in which one or more of its surfaces may slope, or of the number of its hips and valleys, or of the number of its gables 50 having a pitch of the same angle.

What I claim is:

1. The combination in a roof demonstrating device of a body construction consisting of four side walls, a central post supported within said body, radial arms hinged at their inner ends to said post, pins on each arm intermediate its length and near its inner end, and roof sections

each having a pair of openings so located that one of said openings will engage an intermediate pin when the section is assembled on a raised arm and the other of said openings will engage an inner pin when the section is assembled on the 5 arm in its lowered position.

2. The combination in a roof-surface demonstrating device of a body having side walls representing the exterior walls of a building, gable members each comprising a central section and end wings pivoted thereto and having inclined edges of a suitable pitch to represent the front wall of a building gable, a center-post supported within said body, radial arms hinged at their inner ends to said center-post and constructed 10 at their outer ends to interlock with said gable sections, a set of roof members forming a dormer roof and the adjacent portions of a main roof, and means to hold said roof members in place. 15

3. The combination in a roof-surface demonstrating device of a body portion consisting of side walls and cross members, having means for securing a center supporting member in vertical position, a center supporting post having arms adapted to be extended radially therefrom, equilateral triangular shaped members hinged to said side walls, means between said members and arms to support the former in vertical position when said arms are extended radially, and a set 20 of roof members applicable to the members and 25 arms.

4. In a roof-surface demonstrator, a wall, a gable member composed of a central section and end wings, and connections between the wings and central section constructed to hold the wings 30 in extended position with relation to said section to form gable extensions and also in angular position with relation to said section to form dormer sides. 35

5. In a roof-surface demonstrator, a wall, a gable member composed of a central section and end wings, and resilient connections between the wings and central section whereby the wings in extended position with relation to said section to form gable extensions and in inverted position 40 with relation to said section to form dormer sides. 45

6. In a roof-surface demonstrator, a wall, a gable member composed of a central section and end wings having beveled faces formed with tongue and groove joints, and resilient pivotal 50 connections between the wings and central section constructed to hold the wings in extended position with relation to said section to form gable ends and in inverted angular position with relation to said section to form dormer sides. 55

ANNON W. HOLT.
